THERMOSTATIC SWITCH

Robert N. Levinn, Catskill, N.Y., assignor to American Thermostat Corporation, South Cairo, N.Y., a corporation of New York

Filed Sept. 26, 1960, Ser. No. 62,267

Term of patent 14 years

(Cl. D26—13)

FIG. 1

FIG. 2

FIG. 3

FIG. 4

FIG. 5

FIG. 1 is a top plan view of a thermostatic switch, showing my design;

FIG. 2 is a side elevational view thereof;

FIG. 3 is a bottom plan view thereof;

FIG. 4 is an end elevational view thereof taken from the left hand side of FIG. 2; and

FIG. 5 is a cross sectional view taken along the longitudinal center line thereof.

I claim:

The ornamental design for a thermostatic switch, as shown.
